West Monroe Hopkins INVENTOR

UNITED STATES PATENT OFFICE.

NEVIL MONROE HOPKINS, OF NEW YORK, N. Y.

DESICCATING AND INCINERATING RANGE.

Application filed May 25, 1921. Serial No. 472,563.

To all whom it may concern:

Be it known that I, NEVIL MONROE HOPKINS, citizen of the United States, and a resident of New York city, in the county 5 of New York and State of New York, have invented certain new and useful Improvements in Desiccating and Incinerating Ranges, of which the following is a specification.

10 The object of my present invention is to provide a quick and economical method of drying and burning table refuse, using waste thermal units for the desiccating, before chemical fermentation sets in forming 15 garbage. In the present invention I am incorporating with a combination range or cook stove scientific means for evaporating off the water content of table refuse by employing the thermal units from a coal, gas 20 or electric equipment, or the thermal units from a combination of two or more of such heating equipments which would otherwise pass up the chimney after they had served their purpose in the process of cooking.

25 Table refuse both before and after fermentation sets in, requires many thermal units to convert the water content into steam, because of the well known and exceedingly high latent heat of steam, and it is 30 also well known that a cook stove, range or furnace is exceedingly wasteful in thermal units because of the large volumes of hot gases which pass up the chimney.

Whereas the following illustrations depict one design of range or cook stove, it is 35 obvious that this principle may be equally well applied to other designs or to stoves other than cook stoves or to furnaces.

Although I am aware of the fact that 40 efforts have been made to utilize such waste heat units in the art, they have been confined to old style ranges and improperly attempted without due understanding of the difficult problem involved. Table refuse both before and after fermentation is 45 not only difficult to dry out but to incinerate, because it packs and prevents a desiccating draft from passing through and between all of the particles of the mass, and likewise resists burning gases, which fail to 50 pass freely through the close interstices of the material.

For successful operation I find it necessary except where mechanical draft, forced 55 or induced circulation by vacuum of heated gases is resorted to, to distribute the

material to be desiccated over a considerable area and in contact with liberal surfaces of heated metal in order that it may be quickly dried through presenting a large number 60 of contacts with the source of heat when the shrinkage which takes place provides passageway for incinerating flames. Or if the refuse is closely compacted, it is necessary to provide a double path for flue gases 65 both through and around the mass to be desiccated in order that initial drying and subsequent shrinkage may take place thereby opening up routes for flame action. It is also essential to so design and construct 70 the desiccating chamber that incineration also may take place therein without driving out smoke or gases into the room.

The accompanying drawings represent one form of construction of a combination 75 range or cook stove, with a desiccating compartment for receiving table refuse, and combining the described essential features. This range is constructed for cooking with gas, electricity, wood, coal or with any combination of these methods, and is so constructed that the thermal units liberated from the gas section, from the electric section, or from the wood or coal burning section, pass into the desiccating chamber both 80 through and around the table refuse, which by nature of the design and construction, remains greatly spread out and in contact with large surfaces of metal, making it easy to dry, and without impairing a natural 85 draft, or draft resulting from heated and consequently expanded gas columns and consequent effective gravity action on cooler intake air. The gases then pass through the interstices of the shrunken material and 90 then around a baffle plate, up the stove pipe, and into the stack or chimney of the building, where the equipment is installed.

Being so constructed the table refuse is 95 quickly dried out, shrunken and crisp, and it only remains to allow the highly combustible material to slide down into the wood and coal burning or combustion chamber, where the tinder like material is easily ignited. The combustion may also be made, 100 in such a general design as shown, to take place within the desiccating chamber itself.

A clear understanding of the details of one design of invention may be had by 105 reference to the accompanying drawings, where Figure 1 is a top plan view of such a combination equipment, with the doors to

the desiccating compartment closed and cover plates on the top of the stove.

Figure 2 is a front elevation view.

Figure 3 is an end elevation view showing a double walled back, constituting the desiccating chamber with a mechanical draft member above partly in section.

Figure 4 is a top plan view of the same device, but with the mechanical draft mechanism and iron cover plates removed, allowing us to look down into the gas auxiliary compartment at the left, the wood and coal burning chamber in the center, and the electrical heating auxiliary at the right.

Figure 5 is a front view partially in section with the interior of the V shaped desiccating chamber exposed and containing a perforated cast iron cone closing the throat.

Figure 6 is a sectional view of a portion of the parts shown in Fig. 3 and showing up the interior of the desiccating chamber and cone, and Figures 7 and 8 are details of the perforated cast iron cone through which the thermal unit carrying gases escape on their way through and around the refuse to the chimney.

With further reference to Figures 1, 2, 3, 4, 5 and 6, the chute doors which are designed to close air tight, leading into the desiccating chamber, are shown at 10, under the ovens 11. The doors 12 merely lead into compartments underneath the desiccating compartment for keeping dishes, utensils and their contents warm, and out of the way of things cooking on the surface of the range.

The desiccating compartment in the present equipment is formed by the inclined chutes 13 shown in Figure 5. Down these chutes the table refuse slides by gravity until it reaches the cast iron cone 14 having the slotted openings 15, and which is surrounded by a cylindrical cast iron member 16, provided with the vertical slotted openings 17. The member 16 is covered by a dome or bell shaped member 18 which is designed to be raised by the rack 19 through the agency of the pinion 20 on the shaft 21. Said shaft is operated through the agency of the hand wheel 22 shown on the outside of the desiccating compartment in Figures 1, 2, 3, 4, and 6. From this construction it may be seen that a large surface of the material to be desiccated and incinerated is exposed to heated metal as well as to the action of hot gases.

A second rack and pinion 23 and 24 in Figure 6 is mounted upon the same shaft 21 and carries the counter balancing weight 25. Through the agency of this hand wheel on the outside of the desiccating chamber, the iron dome or bell shaped member may be raised and lowered, uncovering more or less of the vertical slots in the cylinder supporting the cone shaped member, and by

continuing to turn the hand wheel after this cast iron dome or bell shaped member has uncovered the full length of these slots, the cone itself is lifted from its seat because of a shoulder 26 shown in Figure 8 in detailed cross section, opening a throat-way into the combustion chamber of the wood and coal burning compartment of the range.

With further reference to Figure 4, the gas section is shown at 28 looking down on a refractory and heat reflecting plate 29, over which play the gas burners 30. The hot gases pass over the refractory member 29, through the opening 50 at the side thereof into the incinerating chamber 27 (see Figure 6) thence upwardly through the openings 15 in the cone 14 and likewise through the uncovered openings 17 in the cylindrical top member 16 and through and over the spread out table refuse to be desiccated on the chutes 13. Then said gases pass around the ends of the baffle plate 31, Figure 5, and thence up the stove pipe 32. In the center at 27 is the coal and wood burning section, the products of combustion from which also pass up through the cone 14 and the refuse to be desiccated. At the extreme right is the electrical heating section where heating wires 34 are shown horizontally disposed over a refractory plate 33. The air heated by these conductors when stove lids or utensils are in place likewise passes out through an opening 50 into the chamber 27, through the cone 14 and the table refuse.

When the range is used in connection with gas or electricity it may be necessary to employ a mechanical draft, or a special means for circulating the heat carrying gases. Here a fan housing 35 see Figure 3, is shown enclosing a fan 36 actuated by a motor 37, and it is obvious from the drawing that the products of combustion may be bypassed directly up the chimney without engagement by the fan through the turning of the dampers 38 and 39. It may likewise be seen that the products of combustion from a wood, coal or coke fire in the wood burning compartment may be made to pass through the slots in the cone, and through the material to be desiccated, with or without the use of mechanical draft.

It is also evident that the natural draft may be varied by uncovering more or less of the vertical slots in the cast iron cone by turning the hand wheel, or by varying the speed of the motor in the mechanical draft, and it is obvious that the table refuse after desiccating may be either allowed to burn in the desiccating chamber or caused to be burned in the combustion chamber by lifting the cone from its seat.

The construction here shown does its work during a period of time comparable with the time required for ordinary cooking proc-

esses. If the material to be dried and burned was not heated both without and within its mass, it would require undue time for the completion of the process.

5 It is also obvious from the construction that any superfluous moisture or water which may be placed in the desiccating compartment with the table refuse, freely passes through the slots in the cone down through 10 the wood and coal burning compartment through the grate 40 and into the water pan compartment 41.

Whereas I have shown a construction illustrating one scheme for the selective use 15 of waste heated products of combustion and of waste heated air adapted to meet the great difficulties of the problem of cheaply drying and incinerating compact wet material, with a large inherent occluded water 20 content, I do not limit myself to the present design, which may be varied without departing from the principle or spirit of the invention. For example I may construct a gas or electric range, or a combination gas 25 and electric range, or a combination of a gas or electric range with a wood and coal, or oil burning range, or any combination thereof, and construct a hood over the same adapted to collect and receive heated waste 30 products of combustion, or waste heated air, the same to be forced or drawn by mechanical means through a desiccating chamber or a combination desiccating and incinerating chamber.

35 Having described one form of my invention, and having set forth its principle and advantages of operation, I claim:

1. In a cook stove, adapted to desiccate 40 garbage, the combination of a lower body portion; an enclosed garbage desiccating chamber above said body portion; a chute for receiving the garbage located in said chamber; a compartment in said chamber below said chute; a member located in said 45 chamber provided with perforations through which hot gases may pass into said chamber; and a baffle disposed in the upper portion of said chamber around which said gases may escape.

50 2. In a cook stove adapted to desiccate garbage, the combination of a lower body portion; a closed chamber disposed above said body portion; a plurality of inclined chutes adapted to receive garbage disposed 55 in said chamber; means comprising a perforated member for admitting hot gases into said chamber; means to open and close the perforations of said member; a baffle disposed in the upper portion of said chamber around which said gases may escape; and means to conduct away said hot gases.

60 3. In a cook stove adapted to desiccate

garbage, the combination of a lower body portion; a closed chamber located above said body portion; a plurality of inclined chutes 65 adapted to receive garbage disposed in said chamber; means comprising a perforated member for admitting hot gases into said chamber; means comprising a rack and pinion to open and close the perforations of 70 said member; a baffle disposed in the upper portion of said chamber around which said gases may escape; and means to conduct away said hot gases.

4. In a cook stove adapted to desiccate 75 and incinerate garbage, the combination of a lower body portion provided with an incinerating chamber; an inclosed garbage desiccating chamber above said body portion; a chute for receiving the garbage located 80 in said desiccating chamber; a member located in said desiccating chamber provided with perforations through which hot gases may pass into said last named chamber, and which normally partially closes an opening 85 between said desiccating and said incinerating chambers; and a baffle disposed in the upper portion of said desiccating chamber around which said gases may escape.

5. In a cook stove adapted to desiccate 90 garbage, the combination of a lower body portion; a closed chamber disposed above said body portion; a plurality of inclined chutes adapted to receive garbage disposed 95 in said chamber; means comprising a perforated member for admitting hot gases into said chamber; means to open and close the perforations of said member; means to raise said perforated member; a baffle disposed in the upper portion of said chamber around 100 which said gases may escape; and means to conduct away said hot gases.

6. In a cook stove adapted to desiccate and incinerate garbage, the combination of a lower body portion comprising an incinerating chamber; a garbage desiccating chamber above said body portion; a chute for receiving the garbage located in said last named chamber; a passage between said incinerating and said desiccating chambers; a 105 perforated member fitting said passage; means to raise said perforated member out of said passage to permit the desiccated garbage to pass down into said incinerating chamber; means to open and close the perforations of said member; a baffle disposed in the upper portion of said desiccating chamber around which heated gases may pass; and means to conduct away the said heated gases.

Signed at New York city in the county of New York and State of New York this 24th day of May A. D. 1921.

NEVIL MONROE HOPKINS.
